UNITED STATES PATENT OFFICE.

HANS ZELLER, OF DUMONT, NEW JERSEY, ASSIGNOR TO EMBROIDERY TRADING COMPANY, OF NEW YORK, N. Y., A CORPORATION OF NEW YORK.

DESIGN FOR EMBROIDERED TRIMMING.

47,092.

Specification for Design.

Patented Mar. 9, 1915.

Application filed November 23, 1914. Serial No. 873,661. Term of patent 3½ years.

To all whom it may concern:

Be it known that I, HANS ZELLER, a citizen of Switzerland, residing at Dumont, county of Bergen, State of New Jersey, have invented a new, original, and ornamental Design for Embroidered Trimming, of which the following is a specification, reference being had to the accompanying drawing, forming a part thereof.

The figure is a plan view of a portion of the trimming, showing my new design.

I claim:

The ornamental design for embroidered trimming, as shown.

HANS ZELLER.
